UNITED STATES PATENT OFFICE.

LUTHER PALMER, OF DEXTER, MICHIGAN.

BASKET-MAKING MACHINE.

SPECIFICATION forming part of Letters Patent No. 516,276, dated March 13, 1894.

Application filed August 16, 1893. Serial No. 483,270. (No model.)

To all whom it may concern:

Be it known that I, LUTHER PALMER, a citizen of the United States, residing at Dexter, in the county of Washtenaw and State of Michigan, have invented certain new and useful Improvements in Basket-Making Machines, of which the following is a specification, reference being had therein to the accompanying drawings.

10 The invention consists in the peculiar construction, arrangement and combination of the various parts.

My machine embodies a frame, a table slid-
15 ingly supported in the frame and carrying a
rotatory form or anvil, means for revolving
the form or anvil automatically, and a tack
feeding and driving mechanism.

My invention comprises the combination of
these various instrumentalities in a single ma-
20 chine and the details of construction of the
various parts, all as more fully hereinafter
described.

In the drawings, Figure 1, is a perspective
25 view of the top of my machine. Fig. 2 is a
vertical, central, longitudinal section there-
through. Fig. 3 is a top plan view thereof.
Fig. 4 is a perspective view of the former or
30 anvil particularly illustrating the mechanism
for rotating the same. Fig. 5 is an enlarged
plan view partly in section of the lower end
of the tack chutes illustrating the manner of
cutting off and feeding the tacks to the driv-
35 ers. Fig. 6 is a similar view showing the
parts in different positions and illustrating
but one of the pair. Fig. 7 is a longitudinal
section on line $\alpha\alpha$ in Fig. 6. Fig. 8 is an ele-
40 vation of the end of the hammer. Fig. 9 is
a sectional elevation illustrating the con-
struction and operation of the inner hoop
holder. Fig. 10 is a perspective view of the
clamping band. Figs. 11 and 12 are views
45 illustrating the material employed in manu-
facturing the box.

A is the frame of the machine, B are the
45 longitudinal timbers at the top thereof hav-
ing guides B' on the sides engaging with the
guides C', of the timbers C forming the main
timbers of the reciprocating table.

D is the table top secured upon the upper
50 faces of the timbers C, and E is a connecting
bar or board connecting the under faces of the
timbers C, the whole forming a sliding table

moving in guides on the stationary longitudi-
nal timbers B which in turn are supported
upon the frame of the machine.

55

E' is a vertical shaft journaled near the
forward edge of the table in the top and bot-
tom cross timbers thereof and carrying at its
upper end a suitable form or anvil F above
the table top, the form or anvil being of the
60 shape of the basket which is to be manufac-
tured.

The basket is made from two or more strips
of veneer, such as is shown in Fig. 11, marked
65 G, which are crossed centrally and secured
together, as shown in Fig. 12. These strips
are usually scored centrally of the ends, as
shown at G'. The strips thus secured to-
gether are shaped upon the form and the in-
70 inner and the outer hoop arranged thereon in
the following manner.

The first step in the
operation is to place the inner hoop G² about
the base of the form, as shown in Fig. 1, the
ends engaging between the hoop holder G³
75 and the form. (The construction and opera-
tion of this hoop holder will be described fur-
ther on.) The veneer pieces secured to-
gether, as shown in Fig. 12, are next placed
upon the form, and the clamping hoop H is
forced down over the ends, causing them to
80 be bent downward over the sides of the anvil
and bind them tightly upon the inner hoop.
The outer hoop is now placed about the ve-
neer, beneath the clamping hoop H, as shown
in Fig. 4, and the button H' on the clamp band
85 is turned over the overlapping ends of the
outer hoop. In this position all that is re-
quired to complete the box is to tack through
the hoops and the ends of the veneer. To
accomplish this the table is moved to and
90 from the tacking mechanism by means of the
lever I pivoted at the rear of the machine and
extending to the front edge thereof in suit-
able proximity to the foot of the operator.

The depression of the lever throws the ta-
ble forward by means of the following mech-
anism: I' is a connecting rod secured at one
end to the lever and at the other end to a
crank I² which is secured at the end of the
shaft J. This shaft carries centrally the crank
100 arm J', which at its lower end is provided
with an antifriction roller J² bearing against
the rail J³ on the post J⁴ depending from the
under side of the cross-bar E of the table.

The rocking of the bell crank J' will cause the roller J^2 to force the post and with it the table toward the tack driving mechanism. The forward movement of the table retracts 5 the inner hoop holder G^3 by the mechanism shown in Fig. 9. The hoop holder consists of a wedge shaped finger projecting through a slot M in the table and at its lower end, provided with an off-set M' engaging in the cam 10 shaped guide way N formed on the inner face of one of the stationary bars B , so that the forward movement of the table will cause the off-set to move down through the inclined portion of the guideway and retract the finger from 15 the hoop. L^2 is a spring acting with its tension to return the carriage to its initial position. In the return movement of the table the anvil is rotated a quarter of a turn, by means of a spring pawl K , engaging with pins 20 K' on the plate K^2 secured to the lower end of the shaft E' which carries the anvil, as plainly shown in Fig. 4. L is a spring bar adapted to bear against the squared face L' of the plate K^2 to hold it and the anvil in its 25 adjusted position, so that the hammers will work squarely against the flat face of the box.

The tacking mechanism is actuated by the movement of the table and it is substantially of the following construction: O is a cross-bar secured on the stationary longitudinal bars of the frame. Upon the upper face of 30 this bar and opposite the anvil are secured the guide plates O' , in which slidingly engage the hammers or drivers O^2 . These hammers at their rear ends are connected together 35 by a cross bar O^3 and are held normally retracted by the tension of the spring O^4 . They are driven forward by the forward movement of the table through the lever O^5 which 40 bears against the rear face of the cross-bar O^3 and which is actuated by the arm P extending forwardly from the post J^4 at the forward end of the table. These hammers or drivers I make of magnetic iron, so that they 45 will attract the tack and hold it thereon while the end of the hammer passes beyond the guides, as shown in Fig. 8 and during the time it is being driven. The tacks are fed to the guides from the receptacle P' which is 50 secured on a frame P^2 pivotally secured to brackets on the cross-bar O . This frame at its rear end is supported upon the notched wheel Q which in turn is supported upon the frame Q' which is hinged at its forward end 55 to the cross-bar P^3 and at its rear end is supported upon the adjusting bolts R , which rest upon the top of the stationary frame, so that by adjusting the frame Q' vertically the angle at which the receptacle P' stands may be 60 varied. S are guide strips in the receptacle to guide the tacks into the guide slot S' . Upon each side of the guide slot are guide ways S^2 which terminate above the chutes T , leading to the guides in the guide plates O' slightly 65 in front of the normal position of the drivers O^2 . T' is a cut-off plate having the inclined

grooves U formed therein, terminating in the enlarged feed aperture U' and forming the needles V which are oscillated across the lower end of the feed chute for the purpose 70 of feeding a single tack at a time into the chute T . The notched wheel Q is rotated by the reciprocations of the table by means of the pawl a carried on the bell crank lever b , which is provided with the anti-friction rolls 75 c bearing against the inclined face d at the forward end of the rails C of the table. The forward movement of the table causes the spring pawl to turn the wheel, as plainly shown in Fig. 2, agitating the frame P^2 and 80 the receptacle P' and causing the tacks to move toward the lower end of the receptacle. The needle bar or cut off T' is actuated by the spring d' secured at one end to the frame of the machine and at the other end to the 85 bar. The bar is provided with a depending roller e extending beside the outer face of a block secured to one of the rails C of the table, which is provided with a cam or incline f so arranged that in the forward movement 90 of the rail G , the roller e rolls up the incline f and moves the bar laterally to the position shown in Fig. 5 allowing a tack to run down in the guide way S' beyond the point of the needle V in the return of the table and the 95 drive mechanism. The spring d draws the cut-off bar down the incline f moving the bar laterally in the opposite direction, to the position shown in Fig. 6, until the enlarged feed aperture U' registers with the mouth of the 100 chute T , allowing the tack which has been cut off by the needle V to fall therethrough and into the guide way in the block O' .

It is obvious from the description given that as the table with its anvil is moved forward toward the driver that the hammer will simultaneously move toward the anvil carrying with it the tack as described, and the tack will be forced through the hoop and veneer of the box and clinched upon the inside. 105 As the table returns to its initial position by the spring L^2 the anvil will be rotated a quarter of a turn presenting a new face to be tacked in the next forward reciprocation. This operation is continued until all four 110 sides of the box have been operated upon when the clamping hoop and box are removed and the operation repeated.

While I have shown my machine applied to manufacturing a four-sided berry box or 115 basket, I may use it in manufacturing berry or other baskets of any desired shape, round, hexagonal, &c., the form or anvil being made of proper configuration.

What I claim as my invention is—

1. The combination of a reciprocating table, a form or anvil carried thereby, and movable tack driving mechanism operated by and in a direction opposite to the table.
2. The combination of a reciprocating table, a form or anvil fixedly held on a plane above the table and pivotally supported therein,

means for horizontally rotating the anvil by the movement of the table, and a tack driving mechanism, substantially as described.

3. The combination of a reciprocating table, 5 a form or anvil fixedly arranged on a plane above the table a vertically pivoted shaft carrying the anvil a spring pawl, a plate on the shaft of the anvil, pins on the plate with which the pawl engages to turn it in the movement of the table, squared faces on the plate and a spring bar adapted to bear against the squared faces to hold the anvil in its adjusted position, substantially as described.

4. The combination of a reciprocating table, 15 an anvil thereon, a vertically reciprocating hoop holder consisting of a finger projecting in its initial position above the table, and a cam way in the stationary frame beside the finger, and a lug on the finger engaging the 20 cam way to retract the finger beneath the table in its forward reciprocation, substantially as described.

5. The combination of a reciprocating table, 25 a form or anvil thereon, a tacking mechanism toward which the table is moved and a hammer actuated toward the anvil by the movement of the table, substantially as described.

6. The combination of a reciprocating table, 30 a form or anvil thereon, a tacking mechanism toward which the table is moved, a tack feed device actuated by the table and hammers

actuated toward the anvil across the feed chute by the movement of the table, substantially as described.

7. The combination of a reciprocating table, 35 a form or anvil thereon, a tacking mechanism comprising a tack receptacle, feed chutes therefrom, a cut-off for the chutes actuated by the retractive movement of the table, and hammers driven toward the anvil by the forward movement of the table, substantially as described. 40

8. The combination in a box making machine of a tack feeding device, guides in which the hammers run and into which the 45 tacks are fed and magnetic hammers running beyond the ends of the guides, substantially as described.

9. The combination in a box making machine of a movable tack receptacle, a notched 50 wheel supporting the rear end of the receptacle, means for rotating the wheel in the actuating of the device, a frame in which the wheel is journaled hinged at its forward end, and an adjustable support for the outer free 55 end of the frame, substantially as described.

In testimony whereof I affix my signature in presence of two witnesses.

LUTHER PALMER.
